RAZOR BLADE SHARPENER

Edward A. Johnston, Chicago, Ill.

Application October 6, 1934, Serial No. 747,170

4 Claims. (Cl. 51—58)

This invention relates to devices for resharpening the edges of razor blades and more particularly to portable sharpeners for razor blades of the double edge wafer type.

5 The main object of the invention is to provide a simple and efficient construction and arrangement of sharpening elements or units so disposed as to embrace both sides of the cutting edge of a blade and to cause relative movements between the sharpening elements and blade of a character best adapted to restore the edge in the shortest possible time. Another object is to produce mechanism of the kind stated which is simple and compact and capable of enclosure in 10 a casing that can be conveniently held in a user's hand during manual operation of the device.

The foregoing, as well as other objects and advantages which will become evident from the detailed description to follow, are accomplished by 20 providing oppositely disposed, rockably mounted, members or heads provided with a novel form of abrading elements between which the blade edge lies and between which heads the blade is slidably held for reciprocation in a novel manner. The 25 invention resides in the organization and details of construction hereinafter claimed, and illustrated in the accompanying drawing, where—

Figure 1 is a side view of the device with one side or wall of the enclosing shell or casing removed to show the contained mechanism;

Figure 2 is a longitudinal section through the device on the line 2—2 of Figure 1;

Figure 3 is a transverse section on the line 3—3 of Figure 1;

Figure 4 is a view of the upper portion of Figure 1 viewed from the right;

Figure 5 is a detail view of one of the rocking members;

Figure 6 is a detail view of a connecting and 40 actuating plate for the rocking members; and

Figures 7 and 8 are plan and edge views, respectively, of the blade holder, Fig. 8 showing the holder with the blade receiving surface turned upward.

45 In the practice of the invention there is preferably provided an oblong rectangular casing 10 containing the blade sharpening mechanism and provided with suitable openings in its walls for insertion of a blade holder or carrier and for the 50 necessary control elements, as will be described.

The sharpening mechanism consists primarily of two oppositely disposed rocker members, having oblong plates or heads 11 and 12 arranged in parallel or facing relation, as illustrated. Each 55 head is rigidly secured to a support consisting of

spaced arms 13 joined intermediate their ends by a connecting plate 14 and having angular extensions 15 to which the heads 11 and 12 are respectively secured. The rocker members are duplicates. As seen in Figure 2, the arms 13 pass around one end of the respective heads and are inclined towards the central longitudinal plane of the casing. The lower ends of the arms 13 of head 11, considered as in the position shown in Figures 1 and 2, are pivotally connected to one end wall of the casing as by a shaft 16 journaled in a bearing 17 secured to one end wall of the casing. The similar arms 13 of head 12 are pivoted at 18 on the ends of a shaft 19 (Fig. 3) carried in the arms of a yoke 20 which in turn is pivoted on a shaft 21 journaled in bearings 22 on the opposite casing wall. The yoke 20 is yielding held on the casing wall by a leaf spring 23 and a push button 24 protrudes from the casing wall and engages the bight portion of the yoke 20, as shown. The axes 16 and 19 of the respective rocker members are thus parallel and located on planes crossing the heads at their transverse centers pivotally. The two rocker members are pivotally joined by a connecting plate 25 having extensions 26 pivoted to the respective arms 13 of the rocker members. The plate 25 has a vertical post 27 which is slotted or forked to engage an eccentric pin 28 on the end of a drive shaft 29 which projects from the casing where it is secured to a crank handle 30. With the structure so far described, it will be clear that rotation of shaft 29 will reciprocate plate 25 and in turn rock the opposed heads 11, 12 on their pivots 16, 19. As the pivot 19 of head 12 is carried by the movable yoke 20, pressure on button 24 will move the heads apart, the purpose of which will be later referred to.

Extending across the casing on a line midway between the heads, there is a guide bar 31 formed with inwardly bent lips 32 (Fig. 2) to form a channel for reception of a slide bar 33 constituting the blade carrier or holder by which a blade is positioned and held between the heads. The bar 33 is provided with spaced studs 34 for engagement in the openings of an ordinary double edge blade 35. One end of bar 33 is formed with a finger-piece or handle 36 with a slot inward therefrom in which is mounted a spring pressed pawl 37 having a nose 38 adapted to interlock with a notch 39 in one end of a swinging lever 40. The other end of lever 40 is pivoted on the end of a shaft 41 held in a bracket 42 secured to the casing wall. Between its ends the lever 40 has a roller 43 at one side which engages in a groove of a cam 55

44 secured on shaft 29. Therefore, rotation of shaft 29 will swing lever 40 and reciprocate holder 33 on guide bar 31 as the heads are being rocked. Pressure on the projecting end of pawl 37 will serve to withdraw nose 38 from notch 39 and release the blade holder or bar 33 for withdrawal. When the holder is inserted the pawl will ride over the inclined end of lever 40 and automatically engage the notch. Pressure on button 24 moves 10 the heads 11, 12 apart to permit insertion or withdrawal of the blade holder and blade.

Both of the oblong heads 11 and 12 are provided at their longitudinal margins with abrasive elements 11a, 12a. These are formed as a series 15 of lugs or teeth (Fig. 1), the surfaces of which are curved on an arc having the axis of the rocker head on which they are mounted as its center, as best shown by Fig. 5. These lugs or teeth on the respective heads interengage at their outer or 20 higher portions, as seen in Figs. 1 and 2, when in parallel or normal position, and move in and out on each other as the heads rock. This arrangement provides a junction line adjacent the cutting edges of a blade along which the concaved abrasive surfaces of the sharpening lugs intersect, and 25 the blade edge is thus in close contact, on both of its sides, with the abrasive during all movements of the heads and blade, as the surfaces of the lugs substantially conform to the bevels of the blade 30 edge.

With the construction and arrangement described, the blade edges will be subjected to both transverse and longitudinal movement while in contact with the abrasive elements between which 35 the blade edges are yieldably held under the pressure of spring 23 which tends to bring the heads together, the holder 33 then serving only to reciprocate the blade. Rapid and effective sharpening effect on the cutting edges is thus assured.

40 It will be obvious that a number of modifications in the specific embodiment of the invention herein disclosed are possible without departure from the scope of the following claims.

What is claimed is:

45 1. A blade sharpener comprising opposite, transversely rockable, sharpener heads having opposed concave abrasive elements positioned to

simultaneously engage the four sides of the cutting edges of a double edge blade, means for reciprocably carrying a blade between said heads with its edges in engagement with the abrasive elements, and driving means for simultaneously 5 rocking the heads transverse to the cutting edges of the blade and reciprocating the blade in the direction of its longitudinal axis.

2. A blade sharpening device comprising a casing, a guide bar extending across the casing 10 formed to receive a blade holder, a removable blade holder on said bar, a sharpener head adjacent each side of the guide bar, each head having an angular extension pivoted on the casing wall on an axis located at the side of the guide 15 bar opposite from the head and extending parallel with the guide bar, opposed abrasive elements along the lateral margins of the heads, said elements on the respective heads having surfaces curved on an arc with the pivot axis of the angular extension of the head as its center, said surfaces being positioned to simultaneously engage the four sides of the edges of a double edge 20 blade when carried by the holder, means for yieldably clamping a blade between said surfaces, 25 and a rotatable driving shaft for rocking both of said heads simultaneously thereby sweeping said arcuate surfaces over the edges of a blade carried by the holder.

3. The combination of claim 2 with the blade 30 holder reciprocable on the guide bar, a lever pivoted within the casing and engaged with the holder, and a cam on the driving shaft having an operating connection with the lever for swinging same to reciprocate the blade holder. 35

4. A blade sharpener comprising parallel sharpener heads having opposed concave abrasive elements formed in spaced portions interfitting with those on the opposite head and positioned to engage opposite sides of the cutting edges of a 40 double edge blade, means supporting said heads for rocking movement about axes extending longitudinally thereof, driving means for rocking said heads in unison, and means for removably inserting a blade between said abrasive elements. 45

EDWARD A. JOHNSTON.
